THEODORE KNUTSON

By Richard Blaum, Attorney

UNITED STATES PATENT OFFICE.

THEODORE KNUTSON, OF NORMA, NORTH DAKOTA.

CLOCK.

Application filed September 9, 1924. Serial No. 736,781.

To all whom it may concern:

Be it known that I, THEODORE KNUTSON, a citizen of the United States, residing at Norma, in the county of Renville and State 5 of North Dakota, have invented certain new and useful Improvements in Clocks, of which the following is a specification.

The present invention relates to a clock and has for its prime object to provide 10 means for operating the clock by the gravity or pressure of water continuously and automatically dripping.

Another important object of the invention is to provide a cheap and reliable power 15 which can be easily applied to produce the necessary motion in a clock mechanism.

Another important object of the invention is to provide a device of this nature which is simple, efficient, strong, and well adapted 20 to the purpose for which it is designed.

With the above and numerous other objects in view as will appear as the description progresses, the invention resides in certain novel features of construction, and in 25 the combination and arrangement of parts as will be hereinafter more fully described and claimed.

In the drawing:

Figure 1 is an elevation of a clock embodying the features of my invention, 30

Figure 2 is a longitudinal vertical section therethrough,

Figure 3 is a top plan view thereof, one end being broken away to show the supply 35 tank partially in horizontal section,

Figure 4 is a longitudinal horizontal section through the clock, and

Figure 5 is an enlarged detail view of the dripping mechanism.

Referring to the drawing in detail it will be seen that 1 represents the casing which may be of any desired formation and is provided in one wall with an opening 2 adapted to receive a closure 3 held in place 45 by any suitable means as at 4. Cleats 5 are provided on the inside of the end walls adjacent the top thereof for supporting a tank 6 adapted to hold water or any other suitable liquid. A filling neck 7 extends upwardly from the supply tank 6 through the top wall of the casing and is provided with any suitable cap 8. A dripping mechanism D is mounted at one end of the tank and consists of a reservoir 9 the lower 50 end of which is tapered and provided with an opening 11 including a valve seat

12. An extension 13 is provided to one side of the reservoir 9 and a pipe or tube 14 leads therefrom and is connected so as to communicate with the tank 6 so that the water or fluid therein may flow through this pipe and keep the reservoir still. A 60 needle valve 15 is associated with the valve seat 12 and extends through the tank and through the top of the casing terminating in a suitable operating knob or the like 16. A portion of the shank of the needle valve is threaded as at 17 into the bottom portion of the tank in order that the amount of liquid dripping from the reservoir 15 may 65 be controlled by moving the needle valve toward or away from its seat 12.

An inverted U-shaped frame 20 is mounted on the bottom of the casing and has journaled therein shafts 21 and 22 which 70 are spaced from each other. These shafts 21 and 22 are also journaled through the front wall of the casing that is the wall opposite to that which has provided therein the opening 2. A clock face of circular 75 construction is mounted on the outside of this wall as is indicated at 23 and the shaft 22 extends centrally therethrough while the shaft 21 is disposed adjacent the edge thereof. These shafts are preferably in the same 80 horizontal plane. A minute hand 24 is provided on the end of the shaft 22 and is adapted to be associated with suitable indicia indicating minutes arranged around the edge of the circular face 23. Additional 85 indicia indicating the hours is arranged on the face and an hour hand 25 is associated therewith being fixed on the outer end of the shaft 21. A housing 26 is provided for the face 23 and a transparent panel is provided therein.

A ratchet wheel 28 is fixed to the shaft 22 as is also a pinion 29. A gear 30 is mounted on the shaft 21 and meshes with the pinion 29. Thus the shaft 21 having mounted thereon a minute hand rotates much faster than the shaft 22 having thereon the hour hand.

A standard 32 rises from the bottom of the casing and supports a lever 33. This lever is pivoted intermediate its end on the top of the standard as at 34. A shovel shaped pan 35 is provided on one end of the lever 33 immediately below the opening in the bottom of the reservoir 9 of the dripping mechanism D. A stop standard or less height than standard 32 and indicated at

36 is provided below this end of the lever 33 having provided thereon the pan 35 so as to limit the swinging of the lever as the drops of water or like fluid engage the pan. 5 A hook shaped dog 37 is pivoted at 38 to the other end of the lever 33 and a spring 39 holds the free end 40 thereof in engagement with the ratchet wheel 28. A weight 41 is adjustably mounted on the lever 33 between the standards 32 and the hooked shaped dog 37. When a drop of water or like fluid hits the pan 35 it will swing the lever so as to move the hooked shaped dog upwardly and when the water flows off of the pan the weight 41 will tend to return the lever to its original position thus partially turning the ratchet wheel 28. It will thus be seen that this ratchet wheel will be intermittently rotated by the drops of fluid from the reservoir 9 and that the feed or frequency of this intermittent motion of the wheel may be controlled by the needle valve 16. This wheel, of course, causes the rotation of the shaft 22 and thereby causes the rotation of the other shaft 21 through the intermediacy of the pinion 29 and the gear 30. A dog 45 is pivoted on one leg of the frame 20 and is adapted to engage the ratchet wheel on an opposite side of the dog 37 so as to prevent rotation of this ratchet wheel in one direction and allowing its rotation in the other direction. In other words the hand 24 is only allowed to rotate in a clockwise direction as long as the pivoted dog 45 is still engaged with the ratchet wheel.

40 A drain cock 46 is provided in the bottom of the casing in order that the same fluid may be used over and over again if desirable. It is thought that the construction and operation of the invention will now be clearly understood without any more detail description thereof.

45 While the preferred embodiment of my invention has been described in detail, it will be understood that I do not wish to be limited to the particular construction set forth, since various changes in the form, material, proportions, and arrangement of parts, and in the details of construction may be resorted to without departing from the spirit or scope of the invention as hereinafter claimed or sacrificing any of its advantages.

50 Having thus described my invention, what I claim as new is:

1. In combination, a casing, a supply tank mounted at the top of the casing, a dripping mechanism associated with the supply tank, a lever fulcrumed in the casing below the supply tank having at one end a pan, a weight adjustably mounted adjacent the other end, liquid from the dripping mechanism adapted to fall on said pan for swinging the lever, a motor mechanism including

a ratchet wheel, a hooked shaped dog on the end of the lever adjacent the adjustable weight, means for holding the dogs in engagement with the ratchet wheel, and a clock hand operable by the motor. 70

2. In combination, a casing, a liquid supply tank mounted in the upper portion of the casing, a dripping mechanism depending from the supply tank including a reservoir having an opening in its bottom forming a valve seat, a needle valve associated with the seat and extending through the tank being threaded therein and also extending through the top of the casing whereby the valve may be moved toward or away from the valve seat for regulating the supply of liquid to drip therefrom, a pipe connecting the reservoir with the tank, a standard rising from the bottom of the casing to a lever fulcrumed intermediate its ends to the top of the standard, a drip pan on one end of the lever and below the reservoir in order that liquid therefrom may drip onto the pan, a stop standard below the end of the lever provided with the pan, a weight adjustably mounted on the other end of the lever, a dog pivotally mounted on the last mentioned end of the lever and provided with a hooked terminal, a frame rising from the bottom of the casing, a shaft journaled in the frame and in one side of the casing, a ratchet wheel on the shaft, a pinion on the shaft, said dog engageable with said ratchet wheel for actuation thereof intermittently, another dog on the frame engageable with the ratchet wheel to allow rotation thereof in one direction only, a second shaft journaled in the frame and in one side of the casing, a gear on said second shaft meshing with the pinion, a minute hand on the exterior end of the first shaft, an hour hand on the exterior end of the other shaft, a clock face on the outside of the casing, indicia on the face for association with the minute and hour hand. 85 90 95 100 105 110

3. In combination, a water supply, a substantially horizontal lever pivotally mounted, yieldable means constantly acting to tilt the lever to a normal position in one direction, a pan on one end of the lever, a water dripping mechanism associated with the water reservoir for supplying drops of water on the pan to intermittently tilt the lever in the other direction against the action of said yieldable means, and a clock hand operating mechanism actuated by said lever, said pan being arranged to discharge the drops of water therefrom upon being tilted by the latter so that the lever will be intermittently returned to its normal position by said yieldable means. 115 120 125

4. In combination, a water dripping mechanism for supplying intermittent drops of water, a movable member, means including a pan movable by each drop of water 130

from said dripping mechanism to intermittently move said movable member, and a clock hand operating mechanism actuated by said movable member, said pan being arranged to discharge each drop of water therefrom after being moved by the latter.

5. In combination, a movable member, a yieldable means constantly acting to move the movable member to a normal position in one direction, a pan on the movable member, a water dripping mechanism for supplying drops of water on the pan to intermittently move the movable member in the other direction against the action of said

yieldable means, and a clock hand operating mechanism actuated by said movable member, said pan being adapted to discharge the drops of water therefrom upon being moved by the latter so that the movable member will be intermittently returned to its normal position by said yieldable means.

In testimony whereof I affix my signature in the presence of two witnesses.

THEODORE KNUTSON.
